UNITED STATES PATENT OFFICE.

ALFRED HEALD, OF PHILADELPHIA, PENNSYLVANIA, ASSIGNOR TO
McCALLUM, CREASE & SLOAN, OF SAME PLACE.

DESIGN FOR A FLOOR-CLOTH PATTERN.

Specification forming part of Design No. 5,881, dated May 28, 1872.

Specification describing a Design for a Carpet or Floor-Cloth Pattern, produced or invented by ALFRED HEALD, of Philadelphia, Pennsylvania.

Design for a Carpet or Floor-Cloth Pattern.

The figure in the accompanying drawing represents sufficient of a carpet or floor-cloth pattern to illustrate my design, which consists of adjoining squares or diamonds, A, B, C, and D, of equal size, arranged to form a check or diamond pattern. Each square A has a central ornament, *a*, composed of stems, leaves, and buds, arranged as clearly shown in the drawing. Each figure B has a foliated ornament, *b*, and from the center of each figure C

radiate four stems, *c*, into and across the adjoining figures D, in each of which dots and short parallel lines are so arranged and shaded off as to form a representation of a leaf upon the stem *c*.

Irrespective of the colors employed, I claim—

The design for a carpet or floor-cloth pattern substantially as described, and as illustrated in and by the accompanying drawing.

In testimony whereof I have signed my name to this specification in the presence of two subscribing witnesses.

ALFRED HEALD.
